(57) **CLAIM**

The ornamental design for a combined cap and adapter for consumable product package, as shown and described.

DESCRIPTION

FIG. 1 is a top right front perspective view of a combined cap and adapter for a consumable product package showing our new design, where the cap is optically transparent and the adapter is optically opaque;

FIG. 2 is a cross-sectional view along line 2-2 of FIG. 1; FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom view thereof;

FIG. 9 is a top right front exploded view thereof;

FIG. 10 is a top right front perspective view of an adapter for a consumable product package showing our new design with the cap removed for clarity of disclosure;

FIG. 11 is a front elevation view thereof;

FIG. 12 is a rear elevation view thereof;

FIG. 13 is a left side view thereof; and

FIG. 14 is a right side view thereof.

FIG. 15 is a top plan view thereof; and,

FIG. 16 is a bottom view thereof.

In the drawings, the evenly-spaced broken lines showing portions of an adapter depict environment and form no part of the claim.
